UNITED STATES PATENT OFFICE.

PETER SHAW, OF BROOKLYN, NEW YORK.

DESIGN FOR A GLOBE, SHADE, &c.

SPECIFICATION forming part of Design No. 23,776, dated November 6, 1894.

Application filed February 14, 1891. Serial No. 381,523. Term of patent 7 years.

To all whom it may concern:

Be it known that I, PETER SHAW, a subject of the Queen of Great Britain, and a resident of the city of Brooklyn, in the county of Kings and State of New York, have invented a certain new and original Design for a Globe, Shade, &c., of which the following is a specification.

This invention is a new and original design for hollow articles of glass ware such as globes, shades and like articles.

Referring to the accompanying drawings forming a part of this specification, Figure 1 is a perspective view of a globe or shade, showing my design and Fig. 2 represents a horizontal section through the lower part of the globe or shade.

My design is particularly applicable to articles of substantially hemispherical shape, and it consists of a hemispherically shaped shade, globe or similar article having on its

exterior surface a series of projecting elliptic lanceolate figures having outer convex or rounded surfaces. The said figures are arranged side by side and each figure is disposed vertically as shown in the drawings, in which—

A represents the globe or shade, and B B indicate the elliptic lanceolate figures, projecting therefrom.

What I claim, and desire to secure by Letters Patent, is—

The design for a globe, shade, &c., substantially as herein shown and described.

In testimony that I claim the foregoing as my invention I have signed my name, in presence of two witnesses, this 13th day of February, 1891.

PETER SHAW.
